ATTORNEY

UNITED STATES PATENT OFFICE.

NELSON UHRY, OF PARIS, FRANCE, ASSIGNOR TO SOCIETE DES GRANDS RESEAUX ELECTRIQUES, OF PARIS, FRANCE, A CORPORATION OF FRANCE.

ARCH FOR THE ELECTRIFICATION OF RAILWAYS.

Application filed August 25, 1923. Serial No. 659,316.

To all whom it may concern:

Be it known that I, NELSON UHRY, engineer, citizen of the French Republic, residing at Paris, Department of the Seine, in France, have invented certain new and useful Improvements in an Arch for the Electrification of Railways; and I do hereby declare the following to be a full, clear, and exact description of the invention, such 10 as will enable others skilled in the art to which it appertains, to make and use the same.

The present invention relates to an arch of novel construction intended for supporting the overhead conductors as well as the supply mains on electrical railways.

The different kinds of wires, cables, etc., which have to be supported in such electrical installations may be enumerated 20 as follows:

1. The overhead conductors.
2. The cables for supplying electric energy, commonly called "feeders."
3. If necessary, high tension feeders, or 25 conductors for transmission of power, either for traction or any other purpose.
4. The conductors usually required for the working of railways, such as signal wires, telegraph wires, telephone wires, 30 wires for distant control, as well as the government telegraph and telephone wires.

In order to comply with the exigences of the service, a great number of such supports are required, and even the smallest saving 35 which may be brought about by a new device may lead to considerable economy in the cost of electrifying railway lines.

The supports ordinarily employed are metal masts of various shapes, reinforced 40 concrete masts and arches spanning the railway lines.

These arches are usually constructed of two different kinds, for example with vertical posts either guyed or not, connected by 45 yielding or rigid cross-ties, or with two pillars dove-tailed at the top to a horizontal beam, which connects them and spans the rails.

The first mentioned kind has the drawback 50 of requiring large foundation blocks, especially in view of the large size of the conductors, which have to be used on main

lines of standard gauge, worked with continuous current at 1500 volts.

The second kind, it is true, allow of the 55 almost complete omission of foundation blocks, but have the drawback of having above the track a girder built up of light iron sections or of small thickness, which constitutes a serious drawback for up-keep 60 and durability, especially on lines which of necessity have to carry mixed traffic for a time.

The arch, which is the subject of the present invention, is of an entirely novel kind, 65 which might be utilized in similar cases of electric transmission of power.

It has all the advantages of self supporting arches and may be made of members requiring very little working, whilst its shape 70 enables it to carry easily all the conductors necessary for the installation.

The accompanying drawing, which is merely diagrammatic, will make it easy to understand in what way the invention may 75 be carried out in practice.

As clearly shown in the drawing, the arch according to the present invention consists of a frame of ogival shape, constituted by two bent members A—A symmetrically located. Like all frames of this kind, it may of course be made without joints like the example shown in the drawing, or with one or three joints as desired. These arches 80 may naturally be made of any materials, 85 but section iron is very suitable. For example either latticed girders or bent section iron of any kind may be used or standard beams or with webs.

With regard to the use of section iron the 90 following remarks may be made:—

The reduction of the bending moment in consequence of the shape chosen, renders it possible to obtain with beams, arches which have a weight comparable with the weight 95 of latticed arches as now used and consequently more economical. They have moreover the advantage over the latter of being built up of members of such thickness that in case of mixed working, electric and steam, 100 they will last almost indefinitely, and will require only very slight up-keep.

On the other hand, the working stress of the constituent beams of such an arch of sec-

tion iron may be considerably higher than that of the constituent members of a lattice arch and may even reach the elastic limit without exceeding it.

5. The longitudinal stability of the arch may be obtained in any way, by guys or struts if necessary.

10. The advantages which are obtained by adopting this shape of arch are the following:—

1. Like any self-supporting arch the size of the foundation blocks is reduced.

2. This arrangement reduces considerably the maximum bending moment.

15. 3. The buttressing of the bent members at the top greatly facilitates the erection of

the arch and readily lends itself to the fixing of one or more high tension conductors at the upper part.

4. This device renders it possible to obtain all the conditions realized by the above mentioned types with a minimum of material.

Claim:

A structure for supporting overhead conductors comprising a relatively light metal frame having vertical legs and inwardly curved upper sections united at their ends forming an ogive or gothic arch. 25

In testimony whereof I affix my signature.

NELSON UHRY.
